UNITED STATES PATENT OFFICE.

JOSEPH NEUBRAND, OF LONG ISLAND CITY, NEW YORK.

AERIAL VESSEL.

SPECIFICATION forming part of Letters Patent No. 361,442, dated April 19, 1887.

Application filed October 14, 1886. Serial No. 210,191. (No model.)

To all whom it may concern:

Be it known that I, JOSEPH NEUBRAND, of Long Island City, in the county of Queens and State of New York, have invented certain new and useful Improvements in Aerial Vessels, of which the following is a specification.

The object of my invention is to provide an aerial vessel or balloon which can be propelled from the car and guided in any desired direction, and thus is under full control of the person occupying the car.

The invention consists in the combination, with a tubular balloon, of a propeller-wheel mounted in the bore of the balloon and connected with pulleys and ropes for operating it from the car, all as will be fully described and set forth hereinafter, and finally be pointed out in the claims.

In the accompanying drawings, Figure 1 is a side view of my improved balloon, parts broken out. Fig. 2 is an end view. Figs. 3 and 4 are side views showing the same in different positions. Fig. 5 is a detail view of the car or basket.

Similar letters of reference indicate corresponding parts.

The balloon C is made tubular, and has a bore, B, extending from end to end. On a transverse bar at each end of the balloon a rudder, A, is pivoted, and to the middle of the swinging end of each rudder two ropes, a, are fastened and extend down to the car or carriage D, provided with a transverse shaft, M, carrying at each end a pulley, N, over which an endless rope, E, passes, said endless ropes also passing over pulleys O at the sides of the balloon, at the center of the same, the pulleys O being fastened to the ends of a shaft, P, passed transversely through the balloon, from which shaft P motion is transmitted, by means of gearing or other device, to a shaft, Q, journaled within the bore of the balloon in cross-pieces R in said bore. These cross-pieces R are connected at their opposite ends to the inner frame of the balloon-body. One or more propeller-wheels, S, are mounted on the shaft Q in the bore of the balloon.

A power-transmitting gear, T, is provided, for revolving the shaft N from the car or basket. To each end of the balloon two ropes,

M, are fastened, which extend down to the car or basket D. The basket or car D is thus suspended from the balloon by means of endless ropes E.

By revolving the shaft M from the car the pulleys N are rotated, and from the same, by means of endless ropes E, the pulleys O, shafts P and Q, and wheels S in the balloon are rotated, whereby the balloon is propelled. By means of ropes a any desired inclination can be given to the rudders A, and the balloon thus steered in the desired direction.

When a rudder is to be inclined in a certain direction, the corresponding rope, a, is drawn taut and fastened on the car or basket, and the other one released correspondingly.

When it is desired that the balloon shall ascend or descend vertically, the ropes m at that end which is to be at the bottom are drawn taut until the balloon stands vertically, as shown in Fig. 3. If the balloon is to ascend or descend at an inclination, the ropes m at one end are tightened, so as to pull down said end, and the ropes at the other end are released, so as to permit said end to swing up.

The body of the balloon for containing the gas may comprise a single annular chamber, as illustrated in Fig. 1, or it may comprise a series of smaller tubes arranged in annular series, as shown by dotted lines in Fig. 3.

Having thus described my invention, I claim as new and desire to secure by Letters Patent—

1. The combination, with a tubular balloon the central bore of which is open at both ends, of propeller-wheels mounted in said bore, substantially as described.

2. A tubular balloon-body having a central bore open at both ends, in combination with transverse bars in its bore, a longitudinal shaft journaled in said transverse bars, propeller-wheels on the longitudinal shaft, and mechanism, substantially as described, for revolving said shaft from the car.

3. The combination, with a tubular balloon-body having a central longitudinal bore, of a longitudinal shaft journaled in the bore of said balloon-body, propeller wheels or wings on said shaft, a transverse shaft extending through the balloon and provided on its ends with pulleys, and ropes passing over said pulleys and

extending down to the car, substantially as described.

4. The combination, with a balloon-body having a central longitudinal bore, of a rudder at each end of said bore, and ropes extending from said rudders to the car, substantially as described.

In testimony that I claim the foregoing as my invention I have signed my name in presence of two subscribing witnesses.

JOSEPH NEUBRAND.
